UNITED STATES PATENT OFFICE

145,956

DESIGN FOR A DRESS

Nathan Shatz, St. Louis, Mo.

Application August 24, 1946, Serial No. 132,837

Term of patent 3½ years

(Cl. D3—26)

To all whom it may concern:

Be it known that I, Nathan Shatz, a citizen of the United States of America, residing in the city of St. Louis and State of Missouri, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is a fragmentary view of the front portion of the dress illustrating the collar portion in open position.

I claim:

The ornamental design for a dress, substantially as shown.

NATHAN SHATZ.
